Des. 180,898
Patented Sept. 3, 1957

180,898

FLINT HOLDER OR SIMILAR ARTICLE

Morton D. Fidler, New York, N. Y., assignor to Ronson Corporation, Newark, N. J., a corporation of New Jersey

Application November 8, 1956, Serial No. 43,698

Term of patent 14 years

(Cl. D58—26)

Fig. 1.

Fig. 2.

Fig. 3.

Fig. 4.

Fig. 5.

Fig. 6.

Fig. 9.

Fig. 7.

Fig. 8.

Figs. 1, 2, 5 and 6 are edge views of a flint holder embodying my invention, taken respectively from the top, left hand and right hand sides, and bottom, of Fig. 3; Figs. 3 and 4 are face views taken respectively from opposite sides of said flint holder;

Figs. 7 and 8 are sectional views taken respectively on the lines 7—7 and 8—8 of Fig. 3; and

Fig. 9 is a perspective view of said flint holder.

I claim:

The ornamental design for a flint holder or similar article, substantially as shown.
